UNITED STATES PATENT OFFICE

2,234,251

RICER CONSTRUCTION

Samuel Hayden and Barney B. Hayden, Chicago,
Ill., assignors to Century Metalcraft Corpora-
tion, Chicago, Ill., a corporation of Delaware

Application June 9, 1938, Serial No. 212,737

4 Claims. (Cl. 248—94)

The invention is directed to colanders of the type usually designated as ricers, and refers particularly to an improved form thereof which has detachable supporting legs, which may be manufactured at a greatly reduced cost, and which has great strength and efficiency.

In use, such devices are subjected to considerable downward pressure and rotative stresses and strains, since the pestle is forced downwardly into the conical container portion and then moved with a circular motion against the walls thereof. The downward and circular strain necessitates a rugged leg mounting structure, and furthermore necessitates a rigid utensil structure. It is also essential that the leg attachment be such that the legs do not work out of their connection with the utensil as the rotative forces are applied.

While the above requirements are present, it is further necessary and preferable that the usual cone shaped body portion be made from relatively light, bendable sheet material, since such material may be most efficiently and cheaply perforated and shaped. In order to strengthen this sheet metal body it is here contemplated that a relatively heavy, cast collar or lip be provided.

Still another important requirement in utensils of the class here involved is that they be so constructed that the possibility of food collecting in inaccessible orifices and the like be reduced to a minimum. Thus, since the cone is of sheet metal and the lip is cast, they are separate parts and must be joined cheaply and in such a manner that flush surfaces are formed at the junction.

To the end that the above requirements may be fulfilled and as a primary object of the invention there is provided herein a device of the above character which comprises a rugged, cast, upper lip or collar portion and a separate lower sheet metal, conical container portion, which portions are secured together permanently in an improved manner so that food will not collect at the junction; with a minimum manufacturing cost, and to provide a rugged joint. It is to be noted that the junction between these parts must be such that they have the characteristics of an integral unit as to strength and regularity or continuity of surface. If, for example, the parts are made from aluminum, welding or spinning methods suffice but are found entirely too costly. Therefore, an efficient mechanical connection such as is provided herein is highly desirable.

Still another object of the invention is to pro-

vide a detachable leg construction which is rugged and whereby the legs, when attached, will not work out of their sockets and will not swivel therein and collapse.

More specifically it is an object of the invention to provide a cast lip portion of a ricer or colander to a sheet metal body portion through a mechanical connection, by interfitting end edges thereof so that the joined surfaces are flush on all sides of the junction, whereby the latter may be easily cleaned and whereby relative movement between the parts is obviated.

It is a further object of the invention to provide a mounting for legs of a colander wherein each leg has a top section extending into a socket positioned radially of the lip or collar to prevent radial hinge movement of the leg, and another top section extending into a socket which is positioned substantially concentrically of the lip or collar to prevent the leg from working out of the sockets under the influence of the rotative forces exerted during the use of the device.

Other objects and advantages of the invention will become apparent from the following description and the accompanying drawing in which:

Fig. 1 is a cross section taken on the line 1—1 of Fig. 3;

Fig. 2 is a cross section taken on the line 2—2 of Fig. 3;

Fig. 3 is a bottom view of the body of the utensil;

Fig. 4 is a fragmentary view of the device showing the leg sockets and a leg attached thereto; and

Fig. 5 is a perspective view of one of the legs.

It is to be understood that the embodiment shown herein may be changed or modified without departing from the spirit of the invention, the scope of which is set out in the appended claims.

The colander or ricer disclosed herein comprises generally an upper, annular, cast, lip or collar 10, a lower perforated, conical, sheet metal container 11, and supporting legs 12, provision for three such legs being made in the present instance.

Referring first to the improved manner in which the lip and cone are secured together: The cone 11 is provided with a perforated wall portion 13 terminating at its lower end in an apex 14 and at its upper periphery in an outwardly extending flange 15 joined integrally with the wall 13 by a relatively sharp bend, as at 16. The lip 10 has a wall portion 17 and terminates at its lower periphery in an inwardly extending

flange 18. In constructing the device the problem presented is to secure the flange 15 of the cone to the flange 18 of the lip in the cheapest manner and yet obtain ruggedness to the extent that the parts will not become separated during use under the forces and strains above set out. Furthermore, the attachment must be made in such a manner that the surface of the utensil at the junction simulates the smoothness of an integral structure to be readily cleaned and to present an attractive appearance.

To accomplish the above, the lower surface of the lip 18 is recessed or grooved from its edge outwardly for a distance equal to the width of the flange 15 of the lip as measured from the corner 16 to the outer edge thereof. It is preferable also that the groove be of a depth equal to the thickness of the sheet material from which the cone is made. Thus it will be seen that when the cone is placed in its proper position relative to the lip, the flange 16 will interfit in the groove and may be riveted to the lip 18 as at 19. It is to be noted that the rivets are driven from the under side so that in the finishing process the upper surface of the flange 18 may be made entirely smooth to be more readily cleaned of food.

From the foregoing it will be seen that when the cone and lip are secured together in the manner described, the upper surface of the flange 18 is left unaffected except for the ends of the rivets which are finished off flush with the surface, that the edge surface of the flange 18 is formed flush with the inner surface of wall 13 by virtue of the relatively sharp corner 16, and that the lower surface of the flange presents no other irregularity than the heads of the rivets; these heads, however, being rounded and very shallow. Thus the relatively cheap mechanical connection provided is free from irregularities which might detract from the appearance of the device and which might collect food particles. It is to be noted also that in practice, when the inner surface of the utensil has been finished, the junction between the corner 16 and the lower rim of the end edge of the flange 18 is not discernible except under close scrutiny. In effect, the cast lip and the sheet metal cone have been mechanically joined in such a manner that they simulate a single unit and have all the desirable characteristics thereof.

Another attribute of the junction described above is its strength. As previously explained, during use the pestle is so manipulated against the cone portion that excessive rotative thrusts are imparted thereto. In a junction such as that shown, which is mechanical, as distinguished from the more expensive methods of welding or spinning the parts together, the problem of relative lateral movement between the cone and the supporting lip during the use of a pestle, is presented. It will be seen that as the pestle is rolled around the inner surface of the cone, the latter is forced laterally of the supporting lip. Continued application of such lateral forces and continued tendency toward relative lateral movement between the parts will in time weaken or loosen the usual mechanical junction and result in a possible separation of the parts. In the present instance this difficulty is overcome by the abutment between the outer edge of the flange 15 and the substantially vertical wall afforded by the groove in the flange 18. It will be understood that since the groove is circular and thus the above abutment relationship extends all around the utensil,

that the cone flange 15 is held laterally immovable in the groove, thus any possibility of relative lateral movement between the parts is obviated.

If desired, the groove may be made in the upper surface of the flange 1, and the cone flange 15 then overlies the upper surface in the groove and extends around the peripheral edge of the lip. As previously stated, in providing detachable legs for a utensil of this character, the attachment must be such that the legs will not work loose during the rotation of the pestle and will not collapse through hinge movement during use. These requirements are fulfilled by the construction shown in Figs. 3, 4, and 5 in which there is shown three sets of lugs depending from the lip 10. Each set comprises a substantially radially extending lug 20 and a substantially concentrically extending lug 21. Each of the lugs has a socket drilled therein to receive the upper end of a substantially U-shaped heavy wire leg 12.

One of these legs is shown in Fig. 5 and consists of upright sections 22 joined for springing relationship to one another at their bottoms. Each of the sections 22 has a horizontally extending section 23 extending from the top thereof, this horizontal section serving as the upper end and connecting element for one of the uprights, while the other horizontal section 23 has, integral with the end thereof, a substantially horizontal section 24 which extends substantially normal thereto and outwardly of the leg assembly. These horizontally extending connecting sections are found to provide extremely efficient support against downward forces exerted during the use of the pestle.

The upright sections 22 are in the present embodiment normally sprung outwardly, and to attach the legs to the lip it is merely necessary to insert the free section 23 into the radial socket of one of the pairs of legs, squeeze the uprights together and continue the insertion into the radial socket until the section 24 is aligned with the respective concentric socket, at which time the uprights are released and the leg is attached as shown in Fig. 4 by movement of the section 24 into its respective concentric socket.

When the legs are so attached it will be seen that they are prevented from working out of their sockets by the angular relationship of the free connecting section 23 and the connecting section 24. Furthermore, swivel or hinge action relative to the utensil is prevented by the radial relationship of the connecting section 23.

The structure shown herein is extremely rugged by virtue of the cast lip and cast lugs and the novel manner in which the legs are attached, and the manufacturing cost thereof is reasonably low by virtue of the novel manner in which the sheet metal cone and cast lip have been attached.

Having thus described our invention, what we claim as new and desire to secure by United States Letters Patent is:

1. In a collar for a colander, a substantially horizontally extending portion, support mounting means depending from said horizontal portion for receiving detachable supporting legs, each of said mounting means embodying a pair of sockets adapted to slidably receive a pair of upper ends of a supporting leg, one of said sockets of each pair being positioned radially of said collar and the other of said sockets being positioned substantially tangentially thereof.

2. In an article of the class described having an annular collar with a substantially horizontal extending bottom flange, in combination, support

receiving means depending from the lower surface of said flange, said means comprising a series of paired, spaced sockets, one socket of each pair extending substantially radially of said collar, the other of said sockets extending substantially tangentially of said collar, and supports, each of said supports comprising a relatively heavy wire leg formed from a single piece of wire and including a pair of upright sections joined at their bottoms, one of said uprights terminating in a substantially horizontally, radially extending section, the other of said uprights having a like, radially extending section and having additionally a further substantially horizontally extending section bent to extend substantially tangent to the collar when the radial section of the other upright is positioned parallel to its respective radial socket, said uprights having a sprung relationship to one another and being so positioned normally that the free ends thereof are spaced farther apart than are the paired sockets.

3. In a collar for a colander, support mounting means associated therewith, said means includ-

ing a series of paired sockets, said sockets being adapted to slidably receive a pair of connecting elements of a supporting leg, one of the sockets of each pair being positioned substantially radially of the collar and the other of the sockets being positioned substantially tangentially thereof.

4. As a new article of manufacture, a supporting leg for utensils or the like, said leg being formed from a single length of relatively heavy wire by bending, and including a pair of upright sections joined integrally at their lower ends by a bridge section for resilient relative movement, one of said uprights terminating at its upper end in a substantially horizontally extending section, said section being positioned at substantial right angles to the bridge section, the other of said uprights having a similarly extending horizontal section and having additionally a further section extending substantially horizontally and parallel to said bridge section.
